UNITED STATES PATENT OFFICE

2,580,925

REFLECTOR OVEN

Kenneth W. Jarvis, Winnetka, Ill.

Application May 28, 1947, Serial No. 750,927

4 Claims. (Cl. 126—274)

1

The present invention relates to a reflector oven, and more particularly to a reflector oven which is collapsible or demountable so as to be readily carried by campers, hikers and sportsmen.

Heretofore reflector ovens have been used by sportsmen, campers and hikers with considerable satisfaction but also with certain disadvantages and inconveniences. Reflector ovens heretofore have not been readily portable nor demountable. The bulk and weight of the reflector ovens thus far available generally has been larger than would be desired by sportsmen, particularly those sportsmen who have to transport the oven by pack.

In accordance with the present invention a collapsible and readily reflector oven is provided which may be folded so as to be stored within a tray which serves to hold the food which is to be cooked, fried, roasted or broiled. This is accomplished by providing a tray which has internal dimensions which are greater than the maximum dimensions of the remaining elements of the reflector oven.

It, therefore, is an object of the present invention to provide an improved collapsible reflector oven.

Another object of the present invention is to provide an improved collapsible reflector oven which is readily stored within the food tray.

Still another object of the present invention is to provide an improved reflector oven which may readily be used for frying food where the heat is to be supplied solely from the underside of the cooking surface.

Still another object of the present invention is to provide an improved reflector oven having a pivoted reflector which may be shifted in position to facilitate certain cooking operations such as basting and turning the food without exposing the user's hand to the heat of the campfire.

A still further object of the present invention is to provide an improved collapsible reflector oven which is readily and economically manufactured of stamped sheet metal.

Other and further objects of the present invention subsequently will become apparent by reference to the following description taken in conjunction with the accompanying drawings wherein:

Figure 1 is a perspective view of the present invention during operation;

Figure 2 is an end view of the invention shown in Figure 1 illustrating the manner in which

2

the top reflector may be tilted to another position;

Figure 3 is a front view of the invention illustrated in Figures 1 and 2;

Figure 4 is an exploded view showing the components of the reflector oven in collapsed or folded position for storage in the food tray; and

Figure 5 illustrates a modified manner of forming the hinged connection between the reflectors and the side members.

The perspective view in Figure 1 illustrates the manner in which the present invention is employed adjacent to a campfire 11 so that the radiant heat therefrom will be reflected by reflector surfaces 12 and 13 to the lower and upper sides of a food tray 14. The lower reflector 12 is connected by hinges 15 and 16 to side members 17 and 18 respectively. Each of the side members 17 and 18 has formed therein a horizontal channel for receiving and supporting the cooking or food tray 14. Thus the side member 17 is provided with a stamped outwardly extending channel 19, and similarly the other side member 18 is provided with a stamped channel 21.

Suitable pivoted or folding legs 22 and 23 are provided for the side members 17 and 18 respectively. The upper reflector 13 is provided with a pair of hinges 24 and 25 which are connected to the side supporting members 26 and 27. The side supporting members 26 and 27 are pivotally connected to the side members 17 and 18 by means of stud bolts having thumb screws 28 and 29. The lower reflector 12 which preferably is formed of a sheet of bright metal may be provided with a plurality of reinforcing ribs or corrugations 31. The upper reflector 13 similarly may be provided with a plurality of ribs 32.

The arrangement of the components of the reflector oven as shown in Figure 2 is the manner in which the oven is commonly used for baking, roasting or cooking. With the oven arranged in this manner it is possible to roast or bake meat and fish, and to bake bread and biscuits. An oven of this type has been employed for cooking or roasting fish, for roasting meat and fowl and for performing generally such cooking operations as are conducted in the oven of the conventional stove.

If during a roasting operation it is desired to turn the roast or to baste it the top reflector 13 may be moved from the position shown in Figure 1 to the position shown in Figure 2 whereupon the food is readily accessible for turning

or basting without exposing the hands of the operator to the heat of the campfire. It, therefore, is unnecessary to lift or turn the present reflector oven in order to have access to the food on the tray 14, as has been the case in other types of reflector ovens.

Where it is desired to use the reflector oven as a cooking means for frying eggs, meats, fish and the like, the oven is employed in the manner illustrated in Figure 2 where the top reflector 13 has been moved to shield the top surface of the food pan 14 from the heat of the campfire. The lower reflector 12 serves to direct the heat to the underside of the food tray 14 thereby to provide an efficient frying surface.

In order to collapse or demount the oven so as to be readily transportable, the wing nuts 28 and 29 are removed from their cooperating stud bolts. The top reflector 13 together with its side members 26 and 27 is then removed from the lower side members, and its side members are folded inwardly so as to appear similar to the central portion of Figure 4. The tray 14 then may be removed whereupon the other side members 17 and 18 connected to the lower reflector 12 are folded inwardly. The one side member such as the side member 18 is provided with a hole 33 so that the one stud may project thereto. Thereupon the wing nuts 28 and 29 are again threaded on to their studs. The one stud and cooperating wing nut 29 as is apparent from the upper portion of Figure 4 therefore serves to hold in position the side members 17 and 18. The legs 22 and 23 are then folded inwardly as shown. Due to the provision of the channel members 19 and 21 in the side members 17 and 18 the maximum dimensions of the reflectors are less than the inside dimensions of the tray 14. Thus, the upper reflector may then be placed in the tray 14 together with its inwardly folded side members 26 and 27. On top of this the bottom reflector 12 together with its inwardly folded side members 17 and 18 and the legs 22 and 23 is placed. The entire collapsed assembly then may be inserted in a suitable bag or container so as to hold the components together and keep them clean.

In the construction thus far shown and described the various hinges 15, 16, 24 and 25 have been shown as being of the piano type retained in position by suitable rivets. As will readily be appreciated by those skilled in the art, it is not necessary to employ hinges of this type since the side members may be provided with suitable separable hinged constructions such as that illustrated in Figure 5. It therefore, is to be understood that where the terms "hinge" or "hinges" are employed in the specification and in the claims, that they are intended to cover all forms of construction which permit the side members to be folded inwardly with respect to the reflector members or to be so collapsed that the side members fit within the food tray 14. For example, the lower reflector 12 may have along its edges a plurality of elongated slots or apertures 35 for receiving suitably formed projecting members 36 which may be integrally formed on the side member 18. In such construction the side members are both hingedly and detachably related to the reflector.

While the side members may be formed of any suitable sheet metal it has been found preferable to employ a bright metal for the reflectors 12 and 13. For economy in manufacture it has been found convenient to employ aluminum alloy or

light gauge stainless steel for the reflectors and for the remaining part of the reflector oven.

While for the purpose of illustrating and describing the present invention, certain preferred embodiments have been shown in the drawings, it is to be understood that the invention is not to be limited thereby since such variations in the construction and in the components employed are contemplated as may be commensurate with the spirit and scope of the invention, set forth in the accompanying claims.

What I desire to protect by United States Letters Patent is claimed:

1. A collapsible reflector oven comprising a pair of vertical triangular side members each having formed therein a horizontal channel for receiving a tray, a single pivoted support leg for each side member arranged to engage said channel in supporting position, a rectangular lower reflector interconnecting said side members below said channel, a rectangular upper reflector connected to two triangular vertical side members, said side members being pivotally connected to said first mentioned vertical side members by thumb screw members, and a tray for said channels having internal dimensions greater than the maximum dimensions of said reflectors or said side members.

2. A collapsible reflector oven comprising a pair of triangular vertical side members of bright sheet metal each having formed therein a horizontal channel for receiving a tray, a pivoted support leg for each side member adapted to engage said channel in oven supporting position, a rectangular sheet reflector interconnecting said side members below said channel at an acute angle thereto, a rectangular sheet reflector connected to two vertical triangular side members, said latter side members being pivotally and separably connected to said first mentioned vertical side members, and a tray for said channels having internal dimensions greater than those of said reflectors or said side members.

3. A collapsible reflector oven of bright sheet metal comprising a pair of vertical triangular side members hingedly interconnected by a rectangular reflector, said side members being arranged to be collapsed relative to said reflector, a second pair of vertical triangular side members hingedly interconnected by a rectangular reflector, said latter side members being arranged to be collapsed relative to said second reflector, thumb screw means for pivotally connecting said latter side members and reflector to the upper portion of said first side members, said first side members each being formed of sheet material having a horizontal channel therein extending outwardly, and a generally rectangular tray having internal dimensions greater than the dimensions of any of said side members and reflectors whereby they may be stored in said tray.

4. A collapsible reflector oven comprising a pair of triangular vertical side members interconnected by a rectangular sheet reflector of bright metal, said side members being arranged to be collapsed relative to said reflector, a second pair of triangular vertical side members interconnected by a rectangular sheet reflector of bright metal, said latter side members being arranged to be collapsed relative to said second reflector, separable means for pivotally connecting said latter side members and reflector to said first side members, said first side members each being formed of sheet material having an

outwardly extending horizontal channel therein, each of said first side members having a leg pivotally mounted thereon to engage said horizontal channel as a stop whenever said leg is in oven supporting position, and a generally rectangular tray having internal dimensions greater than the dimensions of any of said side members and reflectors whereby they may be stored in said tray.

KENNETH W. JARVIS.
